COMBINED DISPLAY RACK AND SIGN HOLDER

Lester M. Mayber, Skokie, Ill., assignor to American Home Products Corporation, New York, N.Y., a corporation of Delaware

Filed Apr. 14, 1966, Ser. No. 1,889

Term of patent 14 years

(Cl. D80—10)

Fig. 1

Fig. 3

FIG. 1 is a top plan view of a combined display rack and sign holder embodying my new design.

FIG. 2 is a front elevational view thereof.

FIG. 3 is a side elevational view thereof.

The essential features of my design reside in the portion shown in solid lines on the drawings.

I claim:

The ornamental design for a combined display rack and sign holder, as shown and described.
